UNITED STATES PATENT OFFICE.

LEBBEUS B. MILLER AND PHILIP DIEHL, OF ELIZABETH, NEW JERSEY.

DESIGN FOR SIDE FRAMES OF SEWING-MACHINES.

Specification forming part of Design No. **11,156**, dated April 15, 1879; application filed January 9, 1879.
[Term of patent 14 years.]

To all whom it may concern:

Be it known that we, LEBBEUS BALDWIN MILLER and PHILIP DIEHL, of Elizabeth, in the county of Union and State of New Jersey, have originated and designed a Side Frame or Support for Sewing-Machines, to be cast of metal or otherwise formed of suitable material, of which the following is a full, clear, and exact description, reference being had to the accompanying photographic illustration, making a part of this specification.

The object of our invention is to design a side frame for a sewing-machine graceful in appearance and symmetrical in the arrangement of its parts.

In the photographic illustration, A is the top and B the bottom portion of the frame, curved and arranged in an open symmetrical form, as shown, attached above and below to the oval frame C, which in turn incloses the letters, devices, and ornaments shown, the said oval frame and the said letters, devices, and ornaments being the trade-mark of the Singer Manufacturing Company, registered June 8, 1875, and numbered 2,651.

The central reversely-curved brace, d, shown in the upper portion of the frame A, connects the cross-bar g to the upper portion of the oval frame C, and the similar central reversely-curved brace, e, connects the lower cross-bar, h, to the lower part of the oval frame.

What we claim as our invention is—

1. The design for a side frame of a sewing-machine, consisting of the top and bottom portions, A and B, the reversely-curved central braces, d and e, the cross-bars g and h, and the oval frame C, as shown in the photograph.

2. A design for a side frame for a sewing-machine, consisting of the portions A, B, C, d, and e, in combination with the letters, devices, and ornaments inclosed within the oval C, as shown.

LEBBEUS BALDWIN MILLER.
PHILIP DIEHL.
